Buell Moore, Houston, Tex., assignor to Esquire, Inc.,
New York, N.Y., a corporation of Delaware

Filed Aug. 3, 1966, Ser. No. 3,347

Term of patent 14 years

The portion of the term of the patent subsequent to
Jan. 21, 1978, has been disclaimed

(Cl. D48—20)

FIG. 1 is a perspective view as seen from one corner and the bottom of the suspended combination transformer and light fixture embodying my design;

FIG. 2 is an enlarged elevational view of one side of the suspended combination transformer and light fixture; and

FIG. 3 is an enlarged view of another side of the suspended combination transformer and light fixture.

The dots on the side walls of the light fixture indicate a roughened surface.

I claim:

The ornamental design for a suspended combination transformer and light fixture, substantially as shown and described.
